JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

BUTTON LOOP

Application filed December 6, 1930. Serial No. 500,447.

This invention relates to an improved wire button loop for use in connection with garments such as overalls and the like, the loop preferably being adapted for suspension 5 from a looped strap and clipped over a button provided by the garment thus supported by the strap. In such type of button loops it is desirable that one size of button loop be adapted for use in connection with buttons 10 having shanks of various diameters and, for that reason, button loops are made with a normally contracted portion which is laterally expandible to permit a shank to pass through the contracted portion from one to 15 the other of axially associated loops. To permit such expansion the wire ends of the button loop are usually secured, one to the other, by means of a second member made in the form of an enclosing clip permitting 20 a relative longitudinal movement of the wire ends within the enclosing clip. The novelty of this invention however resides in such construction of this type of expandible button loop as can be made from one piece of wire 25 of which one end is so flattened and formed as to provide an integral enclosing portion for the reception of the other wire end relatively movable therein.

The objects of the invention are therefore 30 to provide a one-piece expandible button loop of inexpensive manufacture; to provide a strictly one-piece wire device of which one wire end integrally includes a sleeve within which the other wire end is longitudinally 35 movable; and to provide a one-piece wire device including a contracted portion capable of expanding upon the relative longitudinal movement of the wire ends of which one is flattened and formed to receive and substantially conceal the other.

The character of the invention may be best understood by reference to one illustrative device illustrated by the accompanying drawings of which the Figure 1 is an upright elevation 45 of the device in a normal condition; the Figure 2 is a side elevation thereof; the Figure 3 is an upright elevation of the device in an expanded condition; the Figure 4 is a cross-sectional view of a detail upon the 50 line "4-4" of the next previous figure; and

the Figure 5 is an upright elevation of the device in a distorted condition to illustrate parts in perspective.

The device is preferably made of wire but may be made of other forms of metal. As 55 illustrated however the one piece of wire is bent in its middle portion to provide the suspension loop 1 having the horizontal bar 2 around which a strap may be looped. The remaining portions of the wire are then co-operatingly bent to provide the spring side arms 3 and 4 having the normally contracted portion 5 providing a restricted communication between the axially associated loops 6 and 7 adapted for receiving and retaining, 60 respectively, a button first inserted within the loop 6. The wire extremities 8 and 9 are then bent inwardly toward one another in overlapping relation, one of the extremities, 8 for instance, being flattened and 65 formed to resemble in cross-section the letter U and to thus provide the enclosing portion 10 as a continuous and integral part of the side arm 3, as best illustrated by the Figures 70 4 and 5, the enclosing portion 10 having at its outer end the lateral extensions 11 adapted to complete a cylindrical enclosure at that end of the enclosing portion 10. The other extremity 9 is provided with enlargement 12 75 adapted, when the extremity 9 is placed within the enclosing portion 10, to lie and move within the open part of the U-shaped enclosing portion 10. After the extremity 9 is placed within the enclosing portion 10 the extensions 11 are bent around the extremity 80 9 to provide a support therefor and also to provide a stop for engagement by the enlargement 12 upon the full expansion of the button loop.

In use the button loop is clipped over a 85 button which is thereby plunged into the receiving loop 6. As the button loop is pulled upwardly the shank S of the button is urged against the contracted portion 5 of the button loop, as illustrated in dotted line by the 90 Figure 1, whereupon the side spring arms 3 and 4 are made to yield laterally outward, as illustrated by the Figure 3. As the shank S is urged through the contracted portion 5 the extremity 9 longitudinally moves within 95 100

the enclosing portion 10, such relative movement being limited only by the engagement of the enlargement 12 with the bent extensions 11, the resiliency of the spring side arms 3 and 4 being relied upon to return the expanded button loop to its normally contracted condition and thereby retaining the shank S, as illustrated in full line by the Figure 1, within the loop 7.

I claim:

10. 1. A one-piece button loop comprising an expandable wire-loop structure of which one extremity is flattened and formed to provide an enclosing portion of U-shape in cross-section and within which the other wire extremity provided with an enlargement may be enclosed and longitudinally movable upon the expansion and contraction of the structure, the outer end of the enclosed portion being provided with bent extensions to support the enclosed wire extremity and for engagement by said enlargement.
15. 2. A one-piece button loop comprising an expandable wire-loop structure of which one extremity is flattened and formed to provide an enclosing portion of U-shape in cross-section having a longitudinally extending opening and within which portion the other wire extremity may be enclosed and longitudinally movable upon the expansion and contraction of the structure, the outer end of the enclosing portion being provided with bent extensions adapted to support the enclosed wire extremity and to serve as a stop for engagement by an enlargement provided by the enclosed extremity for travel within the longitudinal opening of the enclosing portion.
20. 3. A one-piece wire-loop structure comprising a formed single piece of wire having throughout its length a cross-section of uniform diameter, one extremity of the piece of wire being provided with an enlargement, and the other extremity of the piece of wire being flattened and the flattened portion formed to provide an enclosing portion adapted to receive the enlarged extremity, the outer end of the enclosing portion having bent extensions adapted to support the enclosed wire extremity and to serve as a stop for engagement by the enlargement upon the full expansion of the wire loop.
